DESIGN FOR A LUNCH BOX OR SIMILAR ARTICLE

Everett Worthington, Scarsdale, N. Y., assignor to American Can Company, New York, N. Y., a corporation of New Jersey

Application May 14, 1938, Serial No. 77,199

Term of patent 14 years

To the Commissioner of Patents:

Be it known that I, Everett Worthington, a citizen of the United States, residing at 15 Oak Lane, village of Scarsdale, county of Westchester, and State of New York, have invented a new, original, and ornamental Design for a Lunch Box or Similar Article, of which the following is a specification, reference being had to the accompanying drawing, forming a part thereof.

Figure 1 is a perspective view of a lunch box or similar article showing my new design.

The reverse side of the lunch box is similar in all material respects to the appearance of the article as viewed in the drawing.

I claim:

The ornamental design for a lunch box or similar article, as shown and described.

EVERETT WORTHINGTON.
